UNITED STATES PATENT OFFICE

2,582,112

FIRE EXTINGUISHER

Vernon E. Ferguson, Swan, Mo.

Original application April 23, 1946, Serial No. 664,394. Divided and this application March 26, 1951, Serial No. 217,601

4 Claims. (Cl. 169—31)

1

This invention relates to fire extinguishers operated by fluid pressure and constitutes a division of my application for patent filed April 26, 1946, Serial No. 664,394, on which Patent No. 2,557,957 issued on June 26, 1951.

One of the objects of the invention is to provide a propulsive fluid container in which there is no mixture of such fluid with the fire extinguishing agent and thereby insure that the latter will be discharged in a homogeneous full-strength mass.

Another object of the invention is to provide a construction in which mechanical means is provided to prevent possible mixing of the two fluids or blow-by of the propelling fluid during the discharge of the fire extinguishing fluid.

A further object of the invention is to provide a construction in which the propulsive fluid is permitted to enter the discharge line to follow through and exhaust all of the extinguishing agent.

A still further object of the invention is to provide a fire extinguisher which is operative at any angle in relation to the ground plane.

Another object of the invention is to produce a sealing means for fire extinguishers of the general type described which involves a closure, such as a diaphragm, and a piercing point or knife-edge operated by pressure on the fluid to sever or rupture the sealing diaphragm.

With the general objects named in view and others as will hereinafter appear, the invention consists in certain novel and useful features of construction and organization of parts as hereinafter described and claimed; and in order that it may be fully understood, reference is to be had to the accompanying drawing, in which:

Figure 1 illustrates a central vertical section through a fire extinguisher involving the invention.

Figure 2 is a top plan view of the same.

Figure 3 is a side elevation of the discharge diaphragm rupturing device.

In the said drawing, where like reference characters identify corresponding parts in all of the figures, 1 is a container for fire extinguishing fluid. The upper end of the container is internally threaded to receive a cap 2, said container below the cap being shouldered to receive a permanent partition 3 which is sweated or otherwise seated in a leakproof relation and provides a pair of chambers 4 and 5 respectively, adapted to hold fire extinguishing fluid and a propulsive fluid under pressure. The cap 2 is threaded down against a suitable gasket 6 abutting the parti-

tion 3 so that there will be no leak to the atmosphere. The chamber 5 may be charged through any conventional connection 7 or may be non-rechargeable, if desired.

5 The partition 3 is formed with a through opening or passage which is normally sealed by a closure disc 8, here shown as in the form of a diaphragm. In order to break the disk 8, in the construction shown, any suitable mechanically or electrically operable device may be employed, the construction illustrated showing a piercing point on the end of a screw stem 9 threaded through the cap and provided with an external operating handle 10.

15 To prevent mixing of the propulsive fluid with the fire extinguishing fluid upon the breaking of the disc 8, the chamber 4 is fitted with a piston 11 normally resting in contact with a concentric spacing head 12 projecting from the face 20 of the partition. With this arrangement it will be apparent that when the disc or closure is broken, the propulsive fluid will exert pressure on the piston to compress the fire extinguishing fluid.

25 The discharge end of the fire extinguishing chamber is fitted with a cylinder or tube 13 either attached to the extinguisher directly as shown, or if desired, at the end of a discharge tube or line remote from the container 1. The 30 end of the discharge tube 13 is normally hermetically sealed by a disk or closure diaphragm 14.

35 Mounted within the discharge cylinder or tube 13 is a reciprocating tubular piston 15 having one end formed with a piston head or disk 16, so that when main piston 11 compresses the fire extinguishing fluid, the pressure build up will force piston 15 outwardly to cause its beveled piercing end 17 to sever or cut through the disk 14. The piercing or rupturing end 17 is formed by 40 the bevelled or angular cutting of the tubular piston 15. In order to equalize the pressure on opposite sides of the piston head 16 and to prevent corrosion of the parts, a pin-hole opening 18 is formed in the piston head permitting fire 45 extinguishing fluid to entirely fill tube 13. This is done to prevent possibility of the piston sticking on its seat since slight leakage past the piston would more likely bring about a freezing of the parts.

50 The discharge tube 13 is formed with a pair of oppositely projecting branch tubes or enlargements 19, and the piston tube 15 in the plane of the enlargements is cut away on opposite sides as at 20. Travel of the piston tube in both directions is limited by a stop wire or rod 21 project-

ing through the openings 20 and soldered or attached to the enlargements 19 as shown. Normally the piston stands in its full line position, but when it has been moved by pressure of the fire extinguishing fluid it stands in the dotted line position and the knife edge 17 has cut away or pierced the end 14. The fire extinguishing fluid passes over the head 16 of piston 15 into enlargements 19 and then back through openings 20 for discharge. The stop wire 21 limits movement of the piston so that it cannot interfere with proper discharge by moving too far outwardly. In order that the fire extinguishing fluid may be completely evacuated, a by-pass tube 22 is formed in the lower end of chamber 4. When the piston 11 is stopped by member 23 the by-pass 22 will stand open and the propulsive fluid will scavenge all fire extinguishing fluid out of the discharge line or lines.

From the above description, it will be apparent that I have produced a construction embodying all of the features of advantage set forth as desirable, and which I have described and illustrated the preferred embodiment, it is to be understood that I reserve the right to all changes within the spirit and scope of the appended claims.

I claim:

1. A fire extinguishing device comprising a pair of chambers, one of said chambers being adapted to contain a propulsive fluid and the other a fire extinguishing fluid and having a discharge opening, a diaphragm sealing the discharge opening and broken by an increase in pressure in the fire extinguishing chamber, a closure between the chambers, means to open the closure, a piston in the fire extinguishing chamber adapted to be driven by the propulsive fluid to expel the fire extinguishing fluid, a stop to limit piston travel, and a by-pass tube having its opposite ends connected to the fire extinguishing chamber and points on opposite sides of the piston when the latter is arrested by said stop.

2. A fire extinguishing device comprising a

pair of chambers, one of said chambers being adapted to contain a propulsive fluid and the other a fire extinguishing fluid and having a discharge opening, a diaphragm sealing the discharge opening and broken by increase in pressure in the fire extinguishing chamber, a closure between said chambers, means to open the closure, a piston in the fire extinguishing chamber adapted to be driven by the propulsive fluid to expel the fire extinguishing fluid, and a by-pass tube uncovered by the piston on predetermined travel to permit the propulsive fluid to flow out through the discharge opening behind the extinguishing fluid.

15 3. A fire extinguishing device comprising a pair of chambers, one of said chambers being adapted to contain propulsive fluid and the other fire extinguishing fluid and having a discharge cylinder, a closure normally interposed between the two chambers, means to open the closure, a diaphragm sealing the discharge cylinder, and a piston reciprocating in said cylinder and having a piercing point to rupture the diaphragm when moved by increase in pressure within the fire extinguishing chamber.

20 4. In a fire extinguishing device, the combination of a chamber having fire extinguishing fluid adapted to be discharged under pressure, a discharge cylinder for said fluid, a diaphragm normally sealing the cylinder, and a piston reciprocating in the cylinder and having a piercing point to rupture the diaphragm when moved by increase in pressure in the chamber.
